(57) **CLAIM**

I claim the ornamental design for a trakline belt buckle, as shown and described.

DESCRIPTION

FIG. 1 shows a front perspective view of a trakline belt buckle including a front, bottom, and right side thereof;

FIG. 2 shows a front view thereof;

FIG. 3 shows a rear view thereof;

FIG. 4 shows a top side thereof;

FIG. 5 shows a bottom side thereof;

FIG. 6 shows a right side thereof;

FIG. 7 shows a left side thereof;

FIG. 8 is another front view like that of FIG. 2 but with cross-sectional designations thereon;

FIG. 9 is a cross sectional view taken along the lines 9-9 of FIG. 8;

FIG. 10 is a cross sectional view taken along the lines 10-10 of FIG. 8;

FIG. 11 is a cross sectional view taken along the lines 11-11 of FIG. 8; and,

FIG. 12 is a cross sectional view taken along the lines 12-12 of FIG. 8.
